ALFRED H. GEBHARDT, OF MILWAUKEE, WISCONSIN.

MOLD FOR BATTERY CONNECTERS.

1,415,027.

Specification of Letters Patent. Patented May 9, 1922.

Application filed July 18, 1921. Serial No. 485,712.

To all whom it may concern:

Be it known that I, ALFRED H. GEBHARDT, a citizen of the United States, residing at Milwaukee, county of Milwaukee, and State 5 of Wisconsin, have invented new and useful Improvements in Molds for Battery Connecters, of which the following is a specification.

This invention relates to molds for casting 10 battery connectors and to a method of casting said connectors.

Objects of this invention are to provide a method of casting connectors for batteries, particularly storage batteries, whereby the 15 connectors may be cast in place upon the battery terminals; whereby trimming, fitting and separate casting is avoided; and whereby one operation is employed to both 20 cast and connect the connectors with the proper terminals of the batteries.

Further objects are to provide a mold for casting battery connectors whereby such mold may be positioned about the connectors and the lead alloy or compound poured into 25 such mold to thereby both form the connector and join it to the battery terminals; to provide a mold which may be readily positioned about the battery terminals and may be readily separated to remove it from 30 the cast connector and terminals; and to provide a mold so constructed that it may be used by unskilled labor and will at all times produce a perfect connector in good electrical contact with the battery terminals.

Embodiments of this invention are shown 35 in the accompanying drawings, in which:

Figure 1 is a plan view of the mold.

Figure 2 is a longitudinal sectional view 40 on the line 2—2 of Figure 1 showing the battery terminals in position and a connector cast about them.

Figure 3 is a sectional view similar to Figure 2 showing a modified form of construction.

The process contemplates positioning a 45 two piece mold about the battery terminals which it is desired to connect, pouring a readily fusible alloy into such mold, such alloy conveniently consisting of lead and 50 antimony, allowing such cast connector to harden and thereafter removing the mold. By this process the usual separate casting 55 of the connector, the trimming of the cast

connector, the subsequent fitting and "burning on" is wholly avoided. All of these operations are replaced by the method outlined above.

The method may be extended to include casting of the connectors about frusto-conical sheet metal members previously positioned about the battery terminals. This cone-shaped sheet metal member may, if desired, be coated with a suitable material such as white lead, graphite or other similar material to prevent the adhering of the 60 conical member and the battery terminals. This latter method is applicable under conditions where it is desired to cast accurately fitted connectors which are temporarily 65 positioned about the battery terminals. It is, however, to be noted that both methods contemplate casting the connector in place about the battery terminals and the subsequent removal of the mold 70 therefrom. If the latter method is employed, the connector may be subsequently "burned on" by fusing either a portion of the battery terminals, or by fusing a separate piece of alloy and allowing it to run down about the terminals, thereby joining 75 80 such terminals with the inner portion of the frusto-conical member.

The mold comprises two similar half sections 1 and 2 of malleable cast iron. These sections are provided with pockets or cavities 3 at their ends. These cavities are open at the top and bottom, the bottom opening 4 being relatively smaller and adapted to accurately conform to the larger lower portion 5 of the battery terminals, as indicated 85 in Figure 2. These pockets are joined by a trough-shaped section 6 which is adapted to form the body portion of the connector. The members 1 and 2 are identical in construction and are provided with perforated 90 ears 7 at their ends. A bolt or rod 8 is passed through each of the perforations of the pairs of ears and is provided with headed ends 9 and 10. A compression spring 11 is loosely mounted upon the bolt 100 8 and is adapted to force the two sections into intimate contact as may be seen from Figure 1. A knob 12 may be formed adjacent the middle outer portion of each of the members 1 and 2 and may serve as a 105 manipulating handle for its respective

member to aid in positioning or removing the mold from contact with the battery terminals.

The operation of the device is as follows:

- The sections 1 and 2 of the mold are separated by pulling them apart against the action of spring 11 and are positioned about the battery terminals, as indicated in Figure 2. The members are then released and allowed to move inwardly under the influence of the spring 11 and to contact with each other and with the tapered portions of the battery terminals. Thereafter the connector 13 is formed by pouring the melted alloy into the mold until it is substantially flush with the top of the mold. After the connector has cooled, the sections of the mold are separated against the action of the springs 11 to a sufficient distance to allow the mold to be lifted directly upwardly and to clear all portions of the connector. It will be seen that by this process good electrical contact is secured between the eye portions 14 of the connector and the battery terminals 15. It will also be seen that at one operation, the connector is accurately fitted, formed and connected with the battery terminals.
- The modified form of connector shown in Figure 3 is similar to that previously described except that the pockets 16 are slightly larger than the pockets 3 of the first form and the openings at the lower end of the pockets are also slightly larger. In using this form of mold the battery terminals have a frusto-conical sheet metal member positioned about them. These frusto-conical members may or may not be coated upon their inner surfaces to prevent the adhering thereof to the battery terminals during the casting of the connector 18—the absorption of heat by this conical member

may be great enough to prevent its fusing the battery terminals. These frusto-conical members are to allow the casting and fitting of temporarily removable connectors in position upon the battery terminals. All that is necessary thereafter, is to fuse a portion of the battery terminals or to allow additional fused low melting alloy to run in the space between the conical members 17 and the battery terminals 15.

It will be seen that a mold has been provided whereby connectors may be quickly and expeditiously cast about battery terminals and the mold thereafter removed. It will also be seen that labor of trimming, fitting and subsequent fusing or joining is avoided. In the second type of mold described, it is possible to form removable connectors accurately fitted and shaped and requiring no subsequent work thereon, merely the uniting of the battery terminals with these connectors.

I claim:

1. A mold for casting battery terminal connectors, comprising a pair of sections adapted to be positioned about said battery terminals and having pockets formed in the ends thereof about said battery terminals and spaced therefrom throughout their major portion and having a channel section connecting said pockets, and means for temporarily holding said sections together.

2. A mold for casting battery terminal connectors, comprising a pair of sections adapted to be positioned about said battery terminals and having pockets formed in the ends thereof about said battery terminals and having a channel section connecting said pockets, and a spring adapted to force said members together and into contact with the battery terminals.

ALFRED H. GEBHARDT.
